(57) **CLAIM**

The ornamental design for a moisture-wicking saddle pad, as shown and described.

DESCRIPTION

FIG. 1 is a perspective view of a moisture-wicking saddle pad of the present design, shown as if mounted on a horse; FIG. 2 is a top plan view of FIG. 1 but arrayed on a flat surface in which view the dotted line representing the stitching pattern;

FIG. 3 is a left side elevational view of the saddle pad in FIG. 2, the right side elevational view being a mirror image thereof;

FIG. 4 is a front elevational view thereof;

FIG. 5 is a rear elevational view thereof; and,

FIG. 6 is a bottom plan view thereof.

INVENTOR(S) : Conforth

Page 1 of 4

It is certified that error appears in the above-identified patent and that said Letters Patent is hereby corrected as shown below:

**DELETE DRAWING SHEET 2 AND SUBSTITUTE THEREFOR THE
DRAWING SHEET CONSISTING OF FIG 4-6 AS SHOWN ON THE
ATTACHED PAGES.**

Delete the title page and substitute therefore the attached title page

Delete Drawing Sheets 1-2 and substitute therefor the attached Drawing Sheet 1 and 2.

This certificate supersedes Certificate of Correction issued January 23, 2007.

Signed and Sealed this

Twenty-seventh Day of February, 2007

A handwritten signature in black ink, appearing to read "Jon W. Dudas", is placed over a dotted rectangular background.

JON W. DUDAS
Director of the United States Patent and Trademark Office
